UNITED STATES PATENT OFFICE.

FILLMORE M. SMITH, OF SYRACUSE, NEW YORK, ASSIGNOR, BY MESNE ASSIGNMENTS,
TO JAMES HEDDON'S SONS, INC., OF DOWAGIAC, MICHIGAN, A CORPORATION OF
MICHIGAN.

DESIGN FOR AN ARTIFICIAL BAIT.

59,436.

Specification for Design.

Patented Oct. 18, 1921.

Application filed March 22, 1915. Serial No. 16,290. Term of patent 14 years.

To all whom it may concern:

Be it known that I, FILLMORE M. SMITH, a citizen of the United States, residing at Syracuse, in the county of Onondaga and State of New York, have invented a new and original and ornamental Design for an Artificial Bait, of which the following is a specification, reference being had to the accompanying drawing, forming a part thereof.

Figures 1 and 2 are respectively a top plan and side elevation of the artificial bait showing my new design.

I claim:

The ornamental design for an artificial bait as shown.

FILLMORE M. SMITH.
